UNITED STATES PATENT OFFICE.

WILLIAM C. BOWLEN, OF PROVIDENCE, RHODE ISLAND, ASSIGNOR TO ROCKFORD SILVER PLATE COMPANY, OF ROCKFORD, ILLINOIS, A CORPORATION OF ILLINOIS.

DESIGN FOR A HANDLE FOR SPOONS, FORKS, OR SIMILAR ARTICLES.

No. 38,534.

Specification for Design.

Patented April 23, 1907.

Application filed March 28, 1907. Serial No. 365,208. Term of patent 14 years.

To all whom it may concern:

Be it known that I, WILLIAM C. BOWLEN, a citizen of the United States, residing at Providence, in the county of Providence and State of Rhode Island, have invented a new, original, and ornamental Design for a Handle for Spoons, Forks, or Similar Articles, of which the following is a specification, reference being had to the accompanying drawing, forming part thereof.

The figure is a plan or front view of a handle for spoons, forks, or similar articles, showing my new design.

I claim:

The ornamental design for a handle for a spoon, fork, or similar article, as shown.

WILLIAM C. BOWLEN.
